NURSING BOTTLE HOLDER

Paul B. Aden, Denver, Colo.

Application March 7, 1956, Serial No. 40,500

Term of patent 14 years

(Cl. D83—1)

Fig. 1 is a top view of a nursing bottle holder showing my new design; and

Fig. 2 is a side view thereof.

I claim:

The ornamental design for a nursing bottle holder, as shown.
